HEAD REST FOR A DENTAL CHAIR OR SIMILAR ARTICLE

John T. Armbruster, Niagara Falls, N.Y., assignor to
American Optical Company, Southbridge, Mass.

Filed June 5, 1961, Ser. No. 65,456

Term of patent 14 years

(Cl. D15—3)

FIG 1

FIG 2

FIG 3

FIG 4

FIG. 1 is a side elevational view of a head rest for a dental chair or similar article showing my new design;

FIG. 2 is a front elevational view thereof;

FIG. 3 is a rear elevational view thereof; and

FIG. 4 is a top plan view thereof.

The dotted lines indicating portions of an associated chair are for illustrative purposes only.

I claim:

An ornamental design for a head rest for a dental chair or similar article, as shown and described.
